UNITED STATES PATENT OFFICE.

CHARLES JOSEPH FISHER, OF ALLENTOWN, PENNSYLVANIA.

STAMP-AFFIXING MACHINE.

1,244,724.

Specification of Letters Patent. Patented Oct. 30, 1917.

Application filed July 6, 1916. Serial No. 107,825.

To all whom it may concern:

Be it known that I, CHARLES J. FISHER, a citizen of the United States, residing at Allentown, in the county of Lehigh and State of Pennsylvania, have invented certain new and useful Improvements in Stamp-Affixing Machines, of which the following is a specification.

This invention relates to stamp affixing machines, and more particularly to machines of the class stated in which the stamps are fed from a roll in strip form and secured or affixed to the envelopes through the operation of a lever and plunger mechanism.

One of the main objects of my invention is to provide a machine of the character stated of simple construction and operation. Another object is to provide a machine having special means for moistening the gummed surface of the stamp, and means for separating the individual stamps from the strip of stamps. A still further object is to provide means for securely holding the stamps when an individual stamp is removed or separated from the same. These and further objects are attained by my invention to be described.

In the drawings:

Fig. 1 is a side view of the invention.

Fig. 2 is a side view of the invention showing the parts in operative position, taken from the side opposite to Fig. 1.

Fig. 3 is a vertical central section through the machine.

Fig. 4 is a section on line 4-4 of Fig. 3.

Fig. 5 is a section on line 5-5 of Fig. 3.

Fig. 6 is a detail of the plunger head tripping device.

Fig. 7 is a detail of the stamp slide cover plate, and

Figs. 8, 9 and 10 are details.

Broadly stated, my invention comprises a casing having a shallow cylindrical chamber to receive a roll of stamps in strip form, a plunger head movable in said casing and adapted to tear or detach stamps from the strip, means for feeding the stamp strip across the plunger head and for holding the same during the tearing off or detaching of a stamp, and means for moistening the gummed surface of the stamp previous to its tearing off.

The casing of the machine is formed from two cast sections 1 and 2, each provided with laterally projecting supporting and bracing

webs 3. Each of the sections 1 and 2 is provided, at the center of its inner surface, with an inwardly projecting circular shoulder or flange 4. When the frame is assembled these two flanges cooperate to form a shallow cylindrical chamber 5 adapted to receive a roll of stamps in strip form. This chamber is closed by a door 6 normally held in closed position by a spring catch 7.

The stamp chamber 5 is provided with an upwardly and forwardly directed throat 8 communicating with a slideway in which operates the stamp feeding head 9. This head 9 is carried by a shank 10, the outer portion of which is screw threaded and turned into a sleeve 11 formed integral with a block 12 which operates in guides 13 carried by the parts 1 and 2 of the frame or casing. The block 12 is provided with rearwardly and downwardly directed ears 12a pivoted to the upper end of a rod 14, the lower end of which is pivoted to the arm 15 of an operating bell crank lever 16. The lever 16 is pivoted at 17 between the brackets 18 and 19 formed integral with the casing sections 1 and 2. The lower end of arm 15 of the operating lever is connected by a coil spring 20 to one of the tie rods 21 which secure the parts of the casing together. This spring 20 acts, when the upper arm 16a of the lever is depressed to return it to its normal position.

The forward end of arm 16a of lever 16 is rounded to form a contact head 22. This head is positioned between two lugs 23 projecting from the tubular rod 24 slidably mounted in a sleeve 25 formed by the forward ends of the brackets 18 and 19. Sleeve 25 carries a compression spring 26 confined between a pin 27 located near the top of the plunger rod and a head 28 secured on the upper end of the stem 29 of the plunger foot 30.

A plunger head 31 is mounted in vertical alignment with the foot 30, and is vertically slidable in a guide-way 32 formed between the two sections of the machine casing. This head carries a stem 33 upon the lower end of which is threaded a nut 34. A washer 35 is loosely mounted about the stem, and a coil spring 36 is confined between the nut and the washer. The washer 35 is in engagement with the under surface of a two-armed bracket 37 carried by section 1 of the casing so that the spring 36 normally holds the plunger head in lowered position, as shown in Fig. 3. The head 31 is

provided, at its inner side, with an upwardly and rearwardly inclined plate 38 fitted into a slot in the head, the upper edge of which is serrated to form teeth, for 5 the purpose to be later disclosed.

A shaft 39 is rotatably mounted in the casing adjacent stem 33 of head 31 and carries two forwardly projecting and downwardly curved arms 40 secured thereto, one 10 on each side of the stem 33. The end of shaft 39 which projects through the casing section 2 is squared to receive the lower end of a tripping lever 41 provided with a squared aperture 41^a for this purpose. This 15 lever is secured over the end of the shaft by a screw 42 engaging with the same and threaded into the end of the shaft. At its upper end, lever 41 is pivoted between the arms 43 formed integral with, and at the 20 upper end of, a sleeve 44. At its upper end, the lever 41 is formed with a curved tripping finger 45. This finger is of such length as to engage the head 46 of a spring catch 47 integral with a connecting rod 48 pivotally connected to the supplemental arm 49 25 of the lever 16, when the arm 16^a of the lever has been depressed into its lowest position. The outer part of rod 48 is screw threaded, as at 50, and is inserted into the 30 tubular link 51 which is pivoted to the arm 49. The link 51 is provided with an intermediate elliptical eye 52 which receives a thumb nut 53 threaded on the rod 48. A lock nut 54 is also threaded on the rod adjacent 35 the inner end of sleeve 51. By means of the thumb nut 53 and nut 54, the length of the rod 48 can be adjusted so as to secure accurate operation of the tripping mechanism. A cover 55 is mounted above the 40 slideway in which the feeding head 9 operates. This cover is of shallow rectangular box shape and is of such length as to completely cover the slideway of the feeding head and to project a slight distance rearward of the same. The cover 55 is formed, 45 near its forward end, with lateral downwardly projecting ears 56 which fit into recesses 57 somewhat larger than the ears. A pivot screw 58 is inserted through the 50 ears 56 and the casing thus providing a pivotal mounting for the cover. At its forward end, the cover is provided with a downwardly beveled block 59 of the same width as the feeding head 9. At its rearward 55 end it is provided with two downwardly beveled blocks 60 separated by a central slot 61. A head 62 is mounted to operate between the guides 13 for the feeding head. The body of this head fits snugly 60 between the guides and is provided with integral downwardly and rearwardly projecting lugs 63. The upper end of the rod 14 fits between the lugs 12^a of the block 12, and receives the lugs 63 of the head 62. A 65 cam 64 is mounted between the lugs 63, and

a pivot is passed through the upper end of rod 14 pivotally connecting the same and the lugs 12^a, lugs 63 of head 62, and the cam 64. The cam 64 is of special construction being of an approximately irregular 70 polygonal shape. When the head 62 is in its depressed position, the cam is arranged in a diagonal position with one corner 65 projecting into an approximately triangular recess 66 formed in a guide plate 67 secured 75 to the upper wall of the stamp chamber 5. In this position the front edge 64^a of the cam plate is in engagement with the front edge of the recess 66 of the guide plate and holds the lug 68 formed integral with the 80 cam plate in engagement with the rear edge of the head, thus holding the head in depressed position. When the head is moved rearward, the rear edge 64^b of the cam plate engages the rear edge of the recess 66, at 85 its lower end. The continued rearward movement of the head rotates the cam plate on its pivot 69 so as to bring the edge 64^b in engagement with the upper edge of the guide plate 67 for its full length. When 90 this happens, the lug 68^a carried by the plate 64 engages the under side of head 62 forward of the pivot 69 and acts to rotate the head into raised position. During the movement of the cam plate along the upper edge 95 of guide plate 67 the head is maintained in this position, as indicated in Fig. 8.

When the head 62 is raised, the rear part of the cover 55 is raised by the head thus tilting the cover on the pivot pin 58 so as 100 to bring the front edge of the cover tight against the forward projecting end of the bottom of the slide-way in which the head 9 operates. This acts to hold the stamp strip firmly in position adjacent the inner edge 105 of the plunger head 31. When the upper arm 16^a of the lever 16 is depressed, as in Fig. 2, the rectangular block 12, and the parts connected thereto, are moved rearward by the action of rod 14 pivoted to the 110 lower arm 15 of the lever. This imparts rearward movement to the head 62 which acts in the manner above described to lift the back portion of the cover 55 in the manner above stated. At the same time that 115 this operation is taking place, the plunger head 31 is being moved upward by means of the supplemental lever arm 49, rod 50, lever 41, shaft 39, and the arms 40. As the head rises the toothed edge of plate 38 engages the securely held stamp strip and acts to detach or tear the stamp from the same. Also, as the head rises, the plunger foot 30 is depressed through the action of the head 22 and lugs 23 so as to press firmly downward against the plunger head. By this means, the stamp which has been previously moistened by means to be later disclosed, is tightly pressed against the face of the envelop, which has been placed over the 130

plunger head above the stamp, so as to be firmly secured or attached to the same. As the plunger head reaches its upper most position, the finger 45 of lever 41 acts to trip the catch 47 so as to release the head which is then returned to its initial position through the action of coil spring 36. When the lever arm 16^a has been moved into its lowest position, the cam plate 64 is moved 10 beyond the outer end of guide plate 67. This leaves the head 62 free to be returned to its original position, which is accomplished by means of the beveled blocks 60 secured in the back of cover 55. As the cam plate 15 slides off of the guide plate 67, the head engages these blocks which act to force it backward on its pivot, thus returning it to its original position. At the same time, the back portion of the cover plate returns 20 to its original position, the cover rocking on the pivot pin 58 as before. During the forward movement of the head 62 and cam plate 64, the frictional engagement of the lower edge of the plate with the guide plate 67, acts to rotate the plate forwardly so as to hold the head in lowered position. The stamp feeding head 9 is inclined downwardly and forwardly so as to bring its forward serrated edge 9^a into sliding contact with the bottom of the slide way in which the head operates. This head is provided, at each end, with a rearwardly directed tongue 9^b. This tongue is bent backwardly and upwardly at an angle such that, 30 when the head is in its most forward position, these tongues will be in position to engage over top of the guide plates 13^a mounted in the guide ways 13. By this means, the head, during its rearward movement, is lifted out of engagement with the stamp strip which passes over the bottom of the slideway in which the head operates. The plates 13^a extend rearward to a point adjacent the rear wall of throat 8. When 40 the head has been moved beyond the plates it drops from the rear end of the same onto the bottom of the slideway and is again in position to engage the stamp strip during its forward movement. By this means, each time the lever 16 is depressed and released, the stamp strip is advanced so as to feed a stamp into position over the plunger head 31. The effective length of head 9 may be accurately adjusted by means of the 50 screw threaded shank 10.

A carriage 70 is slidably mounted on the top of plate 55 by means of a bracket 71 secured thereto and carrying a shaft 72 loosely mounted in the bracket provided with rollers 73 engaging the top of plate 55. The forward end of this carriage is provided with an approximately semi-cylindrical casing 74. This casing is provided with a central longitudinal rib 75 provided, at its longitudinal center, with a small aperture 76. A roller 77 of soft rubber or other suitable material is mounted in the casing 74. The bearings of this roller project through arcuate slots in the ends of the casing so as to permit vertical play of the roller, and the 70 roller is provided at its center with a peripheral groove positioned beneath the aperture 76 of rib 75. When the carriage 70 is in its most forward position, the roller 77 rests loosely in the semi-cylindrical recess 78 75 formed in the casing of the machine, at its forward end. A rigid tube 79 is secured to the casing 74 and communicates with the interior of the hollow rib 75. This tube is connected by a flexible tube 80 to a short 80 arcuate nipple 81 communicating with the interior of a tank 82 mounted on needle bearings carried by brackets 83 so as to be freely rockable about a vertical axis. The bracket 71 is provided with an upwardly projecting lug 71^a to which is secured a pivot pin 84. The ends of this pin are mounted in the slotted arms 85 at the lower end of a lever arm 86. The upper end of this arm is pivotally mounted in a slot through the arm 16^a of lever 16, and is bifurcated to receive the lower end of the arm 87, also pivoted in the arm 16^a, the two arms 86 and 87 being mounted on a common pivot 88. The lower end of arm 87 is provided with a forwardly and downwardly projecting shoulder 89 adapted to engage the front edge of arm 86 when arm 87 is rocked forward. A coil spring 90 is mounted about the pivot 88^a with one end inserted 95 into the arm 86 and the other end bearing against the under face of the top wall of arm 16^a of lever 16, as at 91. This spring acts to normally hold the arm 86 in a forward position so that, when the lever 16 is 100 in its normal position, the carriage 70 and the elements carried thereby are positioned at the front of the machine, with the roller 77 resting in the recess 78, as shown in Figs. 1 and 3. With the carriage in this position, the flexible tube 80 is free from all bends so that the water from tank 82 can flow through the same and slowly drip on to the moistening roller 77, any excess of water accumulating in the recess 78 which is made 105 liquid tight for this purpose. The lever arm 87 is provided, at its upper end, with an integral hand plate 92, the under surface of which is provided with an inclined block 93. When the plate 92 is 110 rocked forward, it engages the roller 94 pivotally mounted between the ears 96 formed integral with and projecting from the tube 24 at the upper end thereof. By pressing on the plate 92 the plunger foot 30 115 is forced downward, and the plunger head 31 is forced upward, the stamp being detached from the stamp strip, as previously described. When the plate 92 and arm 87 are swung forward, the arm 86 is swung 120

rearward. This moves the carriage 70 rearward so that the roller 77 passes across the gummed surface of the stamp so as to moisten the same, as will be clear from Fig. 3 of the drawings. During the latter part 5 of the downward movement of the lever arm 16, the arm 86 which operates the carriage 70, will fold upward and rearward, so as not to interfere with the operation of the lever. When the hand plate 92 is released, 10 the spring mounted about the pivot 88 will act to return the carriage 70 to its initial position.

The stamps used in this machine are to 15 be printed or cut into strips, one stamp in width, and these strips are then formed into a roll which is mounted on a pin 97 secured in the casing of the machine at the center of the stamp chamber for this purpose. The 20 stamps are wound with the gummed surface outward and the strip is inserted through the throat 8, over the cross pin 98, and between the leaf spring 99 secured to the pin and the upper rear wall of the throat, into 25 the slideway in which the feeding head 9 operates. When the lever 16 is depressed so as to bring the head 9 into its rearmost position, and then released, the head grips 30 the stamp strip, on its forward movement, so as to feed the stamps toward the plunger head 31, as already described. When a stamp has been fed into position above the 35 plunger head, the hand plate 92 is rocked forward so as to bring block 93 into engagement with roller 95. This moves the carriage 70 to its rearmost position so as to uncover the stamp and, simultaneously, moisten the gummed surface thereof. When the carriage 70 is moved into its rearmost 40 position, the flexible tube 80 is sharply bent, as at 80^a in Fig. 4, so as to cut off the supply of water from the tank 82. This eliminates the possibility of any water dripping through from above the stamp chamber on 45 to the stamp roll. An envelop is then placed with its upper right hand corner above the plunger head 31, and the lever arm 16^a, and plunger foot 30 are forced downward. This forces the stamp into tight 50 engagement with the surface of the envelop so as to become securely attached thereto.

For convenience in operating the machine, suitable supporting brackets 100 and 101 are secured at the front of the machine, at 55 opposite sides thereof, adjacent the plunger head. One of these brackets may support a basket or other suitable container which holds the envelops to have stamps attached. The other bracket may hold the container 60 to receive the envelops to which stamps have been attached.

It will be obvious that various changes 65 may be made in the construction and arrangement of the different parts of my machine without departing from the field and

scope of the invention, and I intend to include all such changes as fall within the scope of the appended claims, in this application, in which a preferred form only of my invention is disclosed.

70

What I claim, is:

1. In a stamp attaching machine, the combination of a slideway, a feed head slidably operable therein, a lever connected to said feed head so as to operate the same, a plunger head mounted adjacent the outer end of the slideway and provided with stamp detaching means, means connected to said lever for raising the plunger head, and a plunger foot mounted above said plunger head and movable toward and away from the same, said foot being connected to the lever so as to be operated thereby.

75

2. In a stamp attaching machine, the combination of a slideway, a stamp feed head 80 slidable therein, an operating lever connected to said head, a plunger head adjacent the upper end of said slideway, means connected to the lever for raising said head, means for holding the stamp strip at a line 90 adjacent the inner edge of the plunger head during the upward movement of said head, and a plunger foot mounted above the said plunger head and movable toward and away from the same, said foot being connected 95 to the said operating lever so as to be operated thereby.

100

3. In a stamp attaching machine, the combination of a slideway, a feed head slidable therein, a rockably mounted cover for said slideway, means for depressing the outer end of said cover during the rearward movement of said feed head so as to grip a strip of stamps fed outward in the slide way, the outer end of the cover being coincident with 105 the outer end of the slide way, a stamp detaching device mounted adjacent the outer end of said slideway adapted to detach a stamp from the outer end of a stamp strip held by the cover, and means for operating 110 the feed head and for simultaneously operating the said detaching device during the rearward movement of the head.

105

4. In stamp attaching machines, a vertically movable plunger head, a plunger foot 115 mounted above said head and movable toward and away from the same, means for feeding a strip of stamps across the plunger head, a holding device adapted to engage the stamp strip along a line in the plane 120 of one face of the plunger head so as to hold the same when the plunger head is raised and permit detaching of a stamp from the strip, a stamp moistening device movable across the plunger head so as to moisten a 125 stamp positioned above the same, a rockably mounted operating lever movable into operative engagement with the plunger foot so as to depress the same when the lever is depressed, connections between said lever 130

and the plunger foot and the stamp feeding means, holding device, and moistening device, and the plunger head for operating the feeding means, actuating the holding device so as to hold the stamp strip fed beneath the same with a stamp positioned above the plunger head, then moving the moistening device across the stamp above the plunger head so as to moisten the same, 5 and subsequently raising the plunger head so as to detach the moistened stamp, when said operating lever for the plunger head is disposed, and means for returning the feed, holding and moistening means and the 10 said plunger head and foot to their initial positions when said lever for depressing the plunger foot is released.

5. In a stamp attaching machine, the combination of a slideway, a feed head slidable 20 therein, a rockable cover plate mounted over said slideway and feed head, means for raising the inner end of said cover during the rearward travel of the feed head, an operating lever connected to said feed head, a 25 plunger head adjacent the outer end of the slideway, means for raising the plunger head during the rearward movement of the feed head, and a plunger foot mounted above the plunger head and movable toward and 30 away from the same, said foot being connected to the operating lever so as to be actuated thereby.

6. In a stamp attaching machine, the combination of a slideway, a feed head slidable 35 therein, means for holding the feed head out of engagement with the bottom plate of said slideway during its rearward movement and in engagement with said plate during its forward movement, a rockable cover plate 40 mounted above said slideway and feed head, means for raising the inner part of the cover plate during the rearward movement of the feed head, a plunger head adjacent the outer end of the slideway and provided 45 with a stamp detaching device, means for normally holding the plunger head in lowered position, means for raising the plunger head during the rearward movement of the feed head, an operating lever connected to 50 the feed head and the plunger head raising means, a tripping device adapted to release the plunger head when it has been raised to a predetermined height, and a plunger foot mounted above the plunger head and 55 movable toward and away from the same, said foot being operatively connected to the said operating lever.

7. In stamp detaching machines, a slide way, a feed head slidable therein, means 60 for holding the feed head out of engage-

ment with the bottom plate of said slide way during its rearward movement and in engagement with said plate during its forward movement, a rockable cover plate mounted above said slide way and feed 65 head, means for raising the inner part of the cover plate during the rearward movement of the feed head, a plunger head adjacent the outer end of the slide way and provided with a stamp detaching device, 70 means for normally holding the plunger head in lowered position, means for raising the plunger head during the rearward movement of the feed head, an operating lever connecting the feed head and the 75 plunger head raising means, a tripping device adapted to release the plunger head when it has been raised to a predetermined height, said tripping device being adjustable whereby the extreme height to which 80 the plunger head is raised may be varied to suit circumstances, and a plunger foot mounted above the plunger head and movable toward and away from the same, said foot being operatively connected to the said 85 operating lever.

8. In a stamp attaching machine, the combination of a casing, a slideway integral therewith, said casing provided with a stamp receiving chamber communicating with the 90 slideway, a feed head slidable in said slideway, a cover plate rockably mounted above the slideway and feed head, means for raising the inner end of the cover during the rearward movement of the feed 95 head, a plunger head mounted adjacent the outer end of the slideway and provided at its inner edge with a serrated plate, an operating lever connected to the feed head, means for normally maintaining the plunger 100 head in lowered position, means connected to the operating lever for raising the plunger head during the rearward movement of the feed head, a tripping device adapted to release the plunger head when 105 it has been raised to a predetermined height, a plunger foot mounted above the plunger head and movable toward and away from the same, a slidably mounted moistening device operable across the plunger head, and 110 means for operating the said moistening device and subsequently depressing the plunger foot and simultaneously actuating the operating lever.

In testimony whereof I affix my signature in presence of two witnesses.

CHARLES JOSEPH FISHER.
